UNITED STATES PATENT OFFICE

PAUL BARGER, OF GREENFIELD, MASSACHUSETTS

WICK

Application filed March 12, 1933. Serial No. 598,498.

This invention relates to kindling wicks for the burners of that type of stoves or heaters which use gaseous or liquid hydrocarbons as fuel.

5 In burners of this type, it is customary to provide one or more wicks, usually circular, of asbestos, or other non-combustible material. When the burner is to be lighted, flame is applied to the wick or wicks and then burn until the necessary initial amount of heat is imparted to the burner.

One pronounced disadvantage of wicks so used is that their lower edges, which, in customary burner construction, rest in oil receiving grooves or troughs, tend to become charred or carbonized as a result of the intense heat to which they are subjected when the oil is exhausted and the dead wick rests upon the heated metal of the trough base. A wick, so charred and carbonized, loses most of its capillarity and must be replaced.

20 The primary object of this invention is to so construct a wick that its absorbent material will never be in direct contact with the metal of the oil trough, thereby preventing carbonization of the wick and assuring a free flow of the oil.

Another object is to so construct a wick 25 material of the character specified that it may be manufactured and sold in flexible strips of non-combustible material of great length, which can be rolled on spools or reels for storage or transportation, pieces of any required length being unwound and cut off to form wicks of any desired shape and size.

A further object is to provide the lower edge of a wick with a series of separated and independent metallic legs or projections, which hold it up out of contact with the base 30 of the oil trough.

A still further object is the provision of a plurality of independent readily attachable metal clips to be secured to and projecting from the base of the wick to serve as supporting legs.

Other objects will appear in and be evident from the following detailed description of the invention.

The invention consists of structural characteristics and relative arrangement of ele-

ments, which will be hereinafter more fully described and particularly pointed out in the appended claims.

In the drawing, in which similar reference characters indicate the same parts in the several figures:

Figure 1 is a perspective view, in central vertical section, of the kindler of a burner, illustrating two oil troughs with wicks there- 55 in;

Figure 2 is a face view of a strip of wick forming material constructed in accordance with this invention;

Figure 3 is a perspective view illustrating the manner in which a portion of material is 60 coiled to form a wick;

Figure 4 is a perspective view illustrating the manner in which a metallic leg forming clip is applied to the lower edge of the strip of absorbent material forming the body of 70 the wick;

Figure 5 is a vertical longitudinal sectional view, in flat projection, through a portion of the center of an oil trough with wick therein, illustrating the manner in which the 75 legs support the absorbent material of the wick free from contact with the base of the groove.

Referring, in the first instance, to Figure 1 of the drawing, there is shown an oil burner kindler structure comprising inner and outer annular troughs 11 and 12 united by bridges 13. Located within each trough, and of such circumference as to be free from contact with the trough walls, is a wick 14 of 80 asbestos, or other non-combustible material, preferably strengthened and reinforced with longitudinally extending interwoven wires 85 15. When the oil in a trough is exhausted and the wick flame has burned out, the sides 90 of the wick, being free from contact with the walls of the trough, suffer from no tendency to char or carbonize.

The wicks are preferably formed from a long strip of material, such as is shown in 95 Figure 2. The lower edge of this strip is provided, at spaced intervals, with independent metallic legs 16, the lower ends of which are adapted to rest upon the base of the trough and hold the wick free from con- 100

tact therewith, so that the lower edge of the same will likewise suffer from no tendency to char or carbonize, as best shown in Figure 5.

6 Each of these spaced, separate and independent supporting legs 16 is preferably in the form of a clip, as shown in Figure 4. Opposite leg members 17, united at their bases, are provided with offset teeth 18, which, 10 when the leg members are positioned embracing the lower edge of the strip of absorbent material and pressed together, pierce such material and serve to fasten the support 16 in proper position upon the strip, as indicated at Figures 3 and 5.

In Figure 3 is shown the manner in which a wick is formed. After the circumference, length or shape of the burner is determined, a sufficient quantity or length of material 20 is cut off from the long strip, shown in Figure 2, and coiled around into annular form with its ends abutting, or so shaped to conform to the contour of the burner. In the drawing, for the purpose of greater clarity, 25 the ends are shown vertically displaced, but the manner in which they abut, and secured together, if so desired, to form the final wick is readily understandable.

In operation, not only are the wicks free 30 from any tendency to char or carbonize on account of touching any of the hot metal of a trough, but such carbon as may form on the lower edge of a wick will burn off as the flame dies out. The elevated position of the wick 35 above the base of the trough permits the flame to burn down the sides of the wick and under its elevated and exposed lower edge, thus automatically consuming any carbon which may have collected there.

40 From the foregoing disclosure of the invention and manner of using the same, all the objects and advantages recited in the statement of invention have been fully and efficiently effected.

45 Of course, it is to be understood that the showing in the drawing is purely illustrative and in no sense constitutes a limitation upon the scope of the invention. Any one skilled in the art can readily see that the absorbent 50 portion of the wick can be of a different nature and the changes that can be made in the metallic clip or supporting leg are many and varied. All changes, alterations and modifications which may be made in the parts 55 shown and described are contemplated as forming part of this invention in so far as they fall within the scope of the following claims.

What I claim is:

60 1. A wick for a hydrocarbon burner, said wick comprising an elongated rectangular thin body of absorbent non-combustible material provided with a plurality of separated and independently attached metallic supporting legs projecting from one of its long edges.

65 2. A wick for a hydrocarbon burner, said wick comprising a rectangular thin body of absorbent non-combustible material and having a plurality of separated metallic members independently secured thereto adjacent the 70 lower edge of the same and extending therebelow.

75 3. A wick for a hydrocarbon burner, said wick comprising a rectangular thin flexible body of absorbent non-combustible material and a plurality of separated and independent metallic clips secured thereto and extending beyond and free of an edge of said rectangular body.

80 4. A wick for a hydrocarbon burner, said wick comprising a rectangular thin body of absorbent non-combustible material and a plurality of separated and independent metallic clips removably embracing and adjustably secured to the lower edge of the same and 85 extending beyond and free of said edge.

85 5. As an article of manufacture, a wick material consisting of a flexible strip of thin rectangular shaped non-combustible material having a series of separated and independent 90 supporting means secured to and projecting from an edge and in the plane of said strip.

95 6. As an article of manufacture, a wick material consisting of a flexible strip of thin rectangular shaped non-combustible material having a series of separated and independent metallic clips embracing and secured to the lower edge of said strip and extending beyond and free of said edge.

100 7. A wick for a hydrocarbon burner, said wick comprising an elongated rectangular thin body consisting of flexible absorbent asbestos fabric provided with a plurality of separated and independent supporting legs attached to and projecting from and below 105 one of the long edges of said fabric.

110 8. An article of manufacture, a wick material consisting of a flexible strip of thin rectangular-shaped non-combustible material having a series of separated supporting legs secured to and projecting from an edge and in the plane of said strip.

115 In testimony whereof, I hereunto affix my signature.

PAUL BARGER. 115
